(57) **CLAIM**

The ornamental design for a diagnostic device, as shown and
described.

DESCRIPTION

FIG. 1 is a perspective view of a first embodiment of a
diagnostic device with the lid in a closed position.

FIG. 2 is a front view of the diagnostic device of FIG. 1;
FIG. 3 is a rear view of the diagnostic device of FIG. 1;
FIG. 4 is a left side view of the diagnostic device of FIG. 1;
FIG. 5 is a right side view of the diagnostic device of FIG.
1;

FIG. 6 is a top view of the diagnostic device of FIG. 1;
FIG. 7 is a bottom view of the diagnostic device of FIG. 1;
FIG. 8 is a perspective view of the diagnostic device of FIG.
1, with the lid in an open position;

FIG. 9 is a front view of the diagnostic device of FIG. 8;
FIG. 10 is a rear view of the diagnostic device of FIG. 8;
FIG. 11 is a left side view of the diagnostic device of FIG.
8;

FIG. 12 is a right side view of the diagnostic device of FIG.
8;

FIG. 13 is a top view of the diagnostic device of FIG. 8;
FIG. 14 is a bottom view of the diagnostic device of FIG. 8;
FIG. 15 is a perspective view of a second embodiment of a
diagnostic device with the lid in a closed position.

FIG. 16 is a front view of the diagnostic device of FIG. 15;
FIG. 17 is a rear view of the diagnostic device of FIG. 15;
FIG. 18 is a left side view of the diagnostic device of FIG.
15;

FIG. 19 is a right side view of the diagnostic device of FIG.
15;

FIG. 20 is a top view of the diagnostic device of FIG. 15;
FIG. 21 is a bottom view of the diagnostic device of FIG. 15;
FIG. 22 is a perspective view of the diagnostic device of
FIG. 15, with the lid in an open position;

FIG. 23 is a front view of the diagnostic device of FIG. 22;
FIG. 24 is a rear view of the diagnostic device of FIG. 22;

(Continued)
